US00D554648S

(12) **United States Design Patent** (10) **Patent No.:** **US D554,648 S**
(45) **Date of Patent:** **** Nov. 6, 2007**

(54) **PORTABLE COMPUTER**

(75) Inventors: **Kevin Massaro**, Houston, TX (US);
Mark Solomon, Cypress, TX (US)

(73) Assignee: **Hewlett-Packard Development
Company, L.P.**, Houston, TX (US)

(**) Term: **14 Years**

(21) Appl. No.: **29/208,042**

(22) Filed: **Jun. 23, 2004**

(51) **LOC (8) Cl.** **14-02**

(52) **U.S. Cl.** **D14/455**; D14/315; D14/318

(58) **Field of Classification Search** D14/315-328,
D14/391-399, 385; D18/1, 2, 7, 11; 235/145 A,
235/145 R; 341/22, 23; 345/104, 156, 168,
345/169, 173; 361/680-686; 400/484-489,
400/492, 472

(57) **CLAIM**

The ornamental design for a portable computer, as shown and described.

DESCRIPTION

FIG. 1 is a perspective view taken from the top and right side of a portable computer showing the new design; and,

FIG. 2 is a top plan view thereof.

The broken lines are shown for illustrative purposes only and form no part of the claimed design.
